PUMPING WELL HOOK-OFF DEVICE

James P. Neel, Valley Center, Kans.

Application November 15, 1938, Serial No. 240,499

3 Claims. (Cl. 74—593)

My invention relates to an improvement in pumping well hook-off devices. It is the practice in the oil fields to install a central power unit which will operate rod or cable lines that in turn operate their respective pump jack at the well. It will be understood that one of these power units will furnish power to pump all the wells on as much as a quarter section or even a whole section of ground at one time, therefor there may be 5 several rod lines run from the power unit to the various wells, or there may be branch rod lines that are connected with a major rod line which furnishes power for several of the branch lines. Each of these branch lines operate a pump jack 10 at their respective well. There are times when it may be desirable to cut off the reciprocal motion of the rod line to some one well and let the others remain in motion. It is the object of my 15 invention to provide a device that will function to engage or disengage any one rod line with the major power line without affecting any of the other rod lines. It is a still further object of my invention to make engagement or disengagement from the power line quickly and without any 20 interruption of the operation of any of the other rod lines. This hook-off device may also be applied to the main power line and may be employed to control the motion of the entire rod system for all the wells at once. A still further object is 25 to provide a device of the kind mentioned that is cheap to make, easy to install, efficient in its work, and one that is durable and long lived. These and other objects will be more fully explained as this description progresses.

Now referring to the accompanying drawing, 30 Fig. 1 is a perspective view showing the device in its engaged position.

Fig. 2 is a perspective view showing the device in its disengaged position.

Fig. 3 is an enlarged detail view, partly in section, showing in detail the action and construction of the engaging and disengaging elements.

Fig. 4 is an enlarged detail sectional view through the guide and stop post, the view being 45 taken along the line IV—IV in Fig. 1.

Similar numerals of reference designate the same parts throughout the several figures of the drawing.

In the drawing is shown a concrete pier or base 50 5. In the upper face of the base 5 is imbedded a plate 6 that is rigidly held in place by a series of bolts 7 that are imbedded in the concrete base 5 and project upwardly therefrom and extend through holes in the plate 6, there being nuts 55

8 threaded on the bolts 7 to rigidly bind the plate 6 to the concrete base 5.

At 9 is shown a vertically positioned pipe, the lower end of which is welded to the plate 6. The pipe 9 is provided with a pair of diametrically opposed slots 10 and 10a. At 11 and 11a is a pair of plates that line the sides of the slots 10 and 10a and extend through the pipe 9. The edges of the plates 11 and 11a are welded to the edges of the pipe 9 at each side of the slots 10 and 10a as indicated at 12 so as to form a rigid side lining 10 through the pipe 9 between the slots 10 and 10a.

Slidably positioned within the slots 10 and 10a and through the post 9 is a draw bar 13. In the rear end of the draw bar 13 is a hole 14 through which is passed a U-shaped element 15, the ends of the legs of which are rigidly clamped between a pair of clamp blocks 16 and 16a that are rigidly clamped onto the outer ends of the legs of the U-shaped element by means of bolts 17. At 18 is 20 shown one end of the rod line that leads to the pump jacks. The inner end of the rod line 18 is provided with a head 19. The inner end of the rod 18 passes loosely through a hole formed between the clamp blocks 16 and 16a so that the 25 head 19 will rest against the clamp blocks 16 and 16a in such a manner that the rod 18 can not be pulled from between the clamp blocks 16 and 16a.

The front end of the draw bar 13 is provided 30 with a coupling hook portion 20 and a stationing hook portion 21. The hook elements 20 and 21 being formed by cutting notches 20a and 21a in the draw bar 13, the notch 20a being cut in the bottom edge of the draw bar 13, and the notch 35 16a being cut in the top edge of the draw bar 13. The notches 20a and 21a are cut so that the hook 20 is positioned at the front end of the draw bar 13, and the hook 21 is positioned somewhat behind the hook 20. At 22 is a pin that passes through the draw bar 13 and projects a short distance on either side of the draw bar 13, the pin 22 is welded to the draw bar 13 so as to provide a permanent and rigid mounting of the pin 22 on the draw bar 13. 40

At 23 is a lever passing through slots such as 45 24 in the pipe 9, the lever being pivotally mounted on a pin 25 that is carried by the pipe 9 so that the lever 23 may be rocked up and down for purposes that will later be made obvious. The pin 25 and lever 23 are so mounted that the rear end of the lever 23 will over-balance the front end of the lever 23 so that as the rear end of the lever 23 drops down the front end of the lever 23 will rise until it engages the upper edge of the 50 55

metal around the slot 24 whereupon the lever 23 is held in substantially a horizontal position.

At 26 is a triangular shaped stop element, which is pivotally mounted at its apex 27 on the front end of the lever 23 in such a manner that the stop element hangs vertically just in front of the pipe 9 and with the base, or cross member, of the triangular stop element suspended just above the top edge of the draw bar 13.

10 At 28 is shown one end of a shaft, the other end of which is connected with a power unit which imparts a reciprocal motion to the shaft 28. The free end of the shaft 28 is slidably supported on a horizontally positioned bar 29 that is carried on a pair of posts 30 that are set in the ground.

15 Rigidly mounted on the free end of the shaft 28 is a bifurcated fitting 31, and the bifurcations are joined together on the top edge and adjacent the outer ends thereof by a bar 32 that is welded 20 to the bifurcation ends.

20 At 33 is a looped link that is provided at one end with a pin portion 33a that is integrally formed on the link 33. At 34 is a bearing element integrally formed on the pin 33a. The pin 33a 25 and bearing 34 are interposed between the bifurcations of the fitting 31. At 35 is a pin on which the bearing 34 is revolvably mounted. The pin 35 passes through the bifurcations at a point a little in the rear of the bar 32, the object 30 of which will later be made obvious.

35 At 36 is an upwardly extending shaft, one end of which is integrally formed on the bearing portion 34. The other end of the shaft 36 is bent rearwardly to form a lever handle 37.

40 The link 33 is made of much heavier material than the lever 36—37, therefore if the link is not supported it will swing downwardly until the shaft 36 will strike the cross bar 32 whereupon the link 33 will be supported in a downward tilted position as shown in Figures 2 and 3.

45 At 38 is a brace element, preferably made of a piece of pipe, one end of which is welded to the plate 6 and the other end is welded to the pipe 9 at a point just below where the draw bar 13 passes through the pipe 9.

50 The operation of the device is as follows: The load of the well is imposed on the rod line 18 and is in the direction of the arrow A at all times. The shaft 28 is connected to the power unit which 55 imparts a reciprocal motion to the shaft 28. The loop or link 33 being hooked as the hook 20 functions to pull the draw bar 13 in the direction of the arrow B and when the power unit moves the shaft 28 in the direction of the arrow C, the load 55 of the pump jack will pull the draw bar 13 in the direction of the arrows A and C, consequently the draw bar 13 takes on a reciprocal motion that is governed by the shaft 28.

60 Now if it is desired to disconnect the draw bar from the power of the shaft 28, the lever 23 is raised so that the base element of the triangular stop element 26 will rest upon the top edge of the draw bar 13, and as the draw moves along in the direction of the arrow A 65 the cross bar, or base element of the triangular stop element 26 will sink into the notch 21a whereupon the hook 21 will engage the cross bar, or base element, of the triangular stop element 26 and push it against the pipe 9 whereupon the motion of the draw bar 13 is stopped 70 and the movement of the link 33 is continued in the direction of the arrows A and C for a short distance to complete the full length of the stroke of the shaft 28. During the continued travel of the link 33 in the direction of the

arrows A and C after the draw bar 13 has stopped, the weight of the link 33 will cause the link 33 to swing downwardly to a point where the shaft 36 engages the cross bar 32 and supports the link 33 in an inclined position such that the outer end of the link is positioned below the hook 20 and the shaft 28 and link 33 5 may continue their reciprocal motion and the draw bar 13 and rod line 18 will continue to stand still.

10 Now if it is desired to connect the draw bar 13 and rod line 18 with the power, all that is necessary to do is to wait until the shaft 28 and link 33 have moved to about their extreme position in the direction of the arrows A and C 15 and at that time press the lever arm 37 downwardly to the dotted position 37a, whereupon the outer end of the link 33 will raise into the notch 21a and on the reverse movement of the shaft 28 and link 33 the link 33 will engage the 20 hook 20 and move the draw bar 13 and rod line 18 in the direction of the arrow B, at which time the triangular stop element 26 is released and the weight of the rear end of the lever 23 will cause that end of the lever 23 to drop to its 25 normal horizontal position whereupon the triangular stop element has been withdrawn from the notch 21a and is again positioned above the upper edge of the draw bar 13 as shown in Fig. 1 so that the reciprocal motions of the shaft 28 30 will be passed on to the draw bar 13 and rod line 18.

35 If for any reason there should be a mishap of any kind and the hook 20 should become disengaged from the link 33 without the triangular stop element being dropped into the notch 21a, the load of the pump jack on the rod line 18 would pull the draw bar 13 rearwardly until the pin 22 would engage the pipe 9 whereupon the movement of the draw bar 13 and rod line 18 40 would be stopped and hold so that no damage could occur.

45 Such modifications of my invention may be employed as lie within the scope of the appended claims without departing from the spirit and intention of the invention. Now having fully described by invention, I claim:

1. In a power hook-off device; said device comprising a stationary base on which is rigidly mounted a retaining and guide element; a shaft that is adapted to be reciprocally driven, a draw bar, and a power transmission line, one end of said power transmission line being connected to one end of said draw bar, the other end of said draw bar having a hook formed thereon that is directed downwardly and in a receding direction from the said shaft, said draw bar having a second hook element formed in the upper edge of said draw bar and also being directed in a receding direction from the said shaft; a stop device, said stop device comprising a lever and a catch element that is pivotally mounted on one end of said lever, said lever being pivotally mounted on said retaining and guide element in such a position that the said catch element will upon the rearward movement of said draw bar fall into engagement with the second said hook and rest against the said retaining and guide element to prevent further rearward movement of the said draw bar; a coupling device for making 70 and breaking connection between said shaft and draw bar, said coupling device comprising a bifurcated element rigidly mounted on the end of said shaft adjacent said draw bar, a link coupling element, said link coupling element 75

having a pivotal mounting between the bifurcations of said bifurcated element, a second lever element, said second lever element being rigidly associated with the said coupling link so that 5 the swing of the coupling link may be governed by the second said lever, said coupling link being so positioned that it may be swung by the second said lever into engagement with the first hook element on said draw bar and will automatically drop from engagement from the first 10 said hook on the said draw bar upon the engagement of the said stop element with the second said hook on the said draw bar.

2. In a power hook-off device as defined in 15 claim 1, a stop pin, said stop pin being rigidly fixed on said draw bar and extending outwardly therefrom on each side therefrom at a point intermediate the first and second said hook ele-

ments on said draw bar so that if the draw bar were released from the coupling link without said stop element engaging the second said hook on the draw bar the stop pin would engage the said retaining and guide element to prevent 5 further rearward movement of the draw bar.

3. In a power hook-off device as defined in claim 2, and stop means on said bifurcated element, said stop means on said bifurcated element being so positioned that the second said lever 10 will engage the said stop on the bifurcated element so as to stop the swing of the said coupling link and hold the coupling link in a position such that it will clear the first said hook element on the said draw bar upon the reciprocal 15 motions of the said shaft.

JAMES P. NEEL.
